INTERNAL COMBUSTION ENGINES

Emilio Tirloni, Cologno al Serio, Italy

Application November 22, 1955, Serial No. 548,485

Claims priority, application Italy February 11, 1955

5 Claims. (Cl. 123—65)

This invention relates to improvements in internal combustion engines and is a continuation-in-part application of my abandoned patent application Serial No. 305,480, filed on August 20, 1952.

An object of this invention is to provide an internal combustion engine with a high thermodynamic efficiency, i. e. with a substantially reduced consumption of fuel per H. P. of power output. Particularly, the aim of this invention is to reduce the exhaust losses substantially—which losses, as already well known, amount in most cases to about 40% of the power developed by the fuel—by providing means designed to greatly improve the combustion of the fuel mixture, through a more complete oxydation of hydrocarbons, as well as through a nearly complete oxydation of CO.

A further object of this invention is to provide an internal combustion engine wherein the exhaust noise level is cut down to a minimum, by means of a relatively low back pressure.

The aforementioned objects are attained according to this invention without a substantial constructive complication or modification of the engines of conventional design through a modification of the thermal flow of the known engines.

Further objects and advantages of this invention will result clearly from a consideration of the following specification of a first and a second embodiment thereof, shown in the accompanying drawing, wherein:

Fig. 1 is a longitudinal sectional view of the cylinder of a four stroke engine, with inlet and outlet valves arranged on the cylinder head.

Fig. 2 is an enlarged detail of Fig. 1 showing an exhaust ball valve as embodied according to the invention in the engine cylinder.

Fig. 3 is a sectional view along the line 3—3 of Fig. 2.

Fig. 4 is a partial view of Fig. 1, viewed in the direction of the arrows 4—4.

Fig. 5 is a longitudinal sectional view of a two stroke engine embodying this invention.

Fig. 6 is a partial elevation view viewed in the direction of the arrows 6—6 of Fig. 5.

Fig. 7 is a sectional plan view taken along the line 7—7 of Fig. 5.

With reference to the first embodiment, as shown by Figs. 1 to 4 inclusive, the improved four stroke engine following substantially a conventional design comprises a cylinder 1 with its head 4 provided with an exhaust valve 2, an inlet valve 3, a threaded hole 5 whereinto a spark plug or an injector (not shown on the drawing) can be mounted. The piston 6 is usually fitted in cylinder 1, and is connected to a crankshaft through a conventional connecting rod unit—not shown, as being outside of the scope of this invention.

According to this invention, a series of automatic ball valves are arranged on the cylinder wall, spaced a distance about $\frac{1}{3}$ of the piston stroke from the lower dead center position of the piston 6 and located on the side

2

of exhaust valve 2. Said valves consist in a housing 8, wherein a ball 7 is freely fitted. The valves are in communication with the inside of cylinder 1 through the duct 9, and with the outside thereof through the duct

5 10 which in turn is connected to a not represented muffler.

The duct 9 communicating with the inside of cylinder 1 is provided with a semispherical valve seat 11, while the duct 10, communicating with the outside, shows too a semispherical seat 12 provided with longitudinal grooves

10 17, through which a communication with the outside and with the housing 8 is established even when the ball 7 is seated against the seat 12. By means of the above mentioned arrangement, the ball 7 will be firmly seated against its seat 11, when a vacuum is produced in the

15 cylinder, i. e. during the induction of fuel mixture, thereby interrupting communication between the inside of the cylinder and the outside, and thus preventing any alteration of the mixture ratio or a cooling of the mixture, which might be caused by an addition of inflowing air.

20 On the other hand, when an over-pressure occurs in the cylinder during the end of expansion stroke, the communication of the cylinder with the outside is maintained through the aforementioned longitudinal grooves 17. By means of a cam timing gear of the already known type,

25 the exhaust valve 2 is opened a short moment ahead of the time in which the exhaust ports 9 are left open by the piston in its expansion stroke. A modification of the thermal flux is thereby caused through the exhaust ball valves 7, and the combustion of the mixture is im-

30 proved, whereby the whole fuel mixture is completely burnt as can be ascertained through a suitable analysis which will show the total absence of CO and dissociated hydrocarbons in the exhaust gases. Moreover, the supplemental lowering of the pressure caused during the ex-

35 haust stroke by the automatic ball valves, cuts the noise down at a satisfactory level, whereby, at the same time, the efficiency of the engine is increased. In addition, as it can be readily appreciated, even the cylinder cooling is improved by the arrangement according to the invention,

40 whereby an overloading of the engine—or, with other words—an increase in the power output in respect to conventional engines—is made possible.

Referring particularly now to Figs. 5 to 7 inclusive, wherein the same components are designated with the same references, the cylinder 1 shows one exhaust port 13 and two inlet ports 14, located substantially adjacent to, and on either side of said exhaust port 13, spaced $\frac{1}{3}$ of the piston stroke from its lower dead center position. According to this invention, a series of automatic ball

45 valves, of the same construction as before described and illustrated, are fitted opposite to the exhaust port 13.

50 5 is the inlet port for admitting the mixture in the crankcase 16, from where it is caused to flow, in the already known manner, by the piston 6, through the inlet ports 2, into the cylinder 1.

55 While two preferred embodiments of this invention have been shown and described, it is to be understood that the description has been given for illustration purposes only, and some modifications are possible without departing from this invention. For instance the invention could be applied either to one, or to multicylinder engines, of the Otto or diesel cycle, and with any arrangement of the inlet or exhaust valves.

60 What I claim is:

65 1. In an internal combustion engine, in combination, a cylinder formed with inlet and exhaust ports through which a fresh charge is admitted into and a burnt charge is discharged from said cylinder, respectively, said cylinder being formed approximately one third of the way

70 from the bottom to the top dead center positions of a piston slideable in said cylinder with at least one opening passing through the wall of said cylinder; and ball valve

means carried by said cylinder at the exterior thereof and communicating with said openings thereof for closing said opening when the latter is uncovered by the piston and the pressure outside of said cylinder is greater than the pressure therein and for providing a limited flow of fluid from the interior of said cylinder through said opening thereof when the pressure within said cylinder is greater than the pressure outside of said cylinder and said opening is uncovered by the piston, said ball valve means including a housing having a hollow inner space communicating with said opening and a ball member in said housing of a smaller size than said hollow inner space, said housing having in its interior a first valve seat surrounding said opening and receiving said ball member to close said opening when the latter is uncovered by the piston and the pressure outside of the cylinder is greater than the pressure therein and said housing having a second valve seat opposite from said first valve seat and receiving said ball member when said opening is uncovered and the pressure within said cylinder is greater than the pressure at the exterior thereof, said housing being formed with at least one passage passing around said ball member from the interior of said housing to the exterior thereof when said ball member is on said second valve seat so that said passage provides said limited flow of fluid from the interior of said cylinder.

2. In an engine as recited in claim 1, said opening of said cylinder being located at a side thereof opposite from a side of said cylinder where said exhaust port thereof is located.
3. In an engine as recited in claim 1, said opening of said cylinder being located at a side thereof which is the same as a side of said cylinder where said exhaust port thereof is located.
4. In an engine as recited in claim 1, said opening of said cylinder being located at approximately the same elevation as and opposite from said exhaust port.
5. In an engine as recited in claim 1, said cylinder being formed with a plurality of openings in addition to said one opening arranged in a row therewith and distributed circumferentially part of the way about the axis of said cylinder, and a plurality of additional identical ball valve means respectively cooperating with said additional openings in the same way as the ball valve means which cooperates with said one opening.
